SLIDER FOR FASTENERS AND PROCESS OF MAKING THE SAME

Filed Dec. 30, 1926

UNITED STATES PATENT OFFICE.

GEORGE E. PRENTICE, OF BERLIN, CONNECTICUT.

SLIDER FOR FASTENERS AND PROCESS OF MAKING THE SAME.

Application filed December 30, 1926. Serial No. 157,952.

This invention pertains to separable fasteners of that general type of which an early example is disclosed in the patent to Judson No. 504,038, August 29, 1893, and relates 5 more particularly to an improved slider for such a fastener and to a process of making such slider.

A common form of slider for use in such fasteners comprises spaced front and rear 10 wings or plates united at one end, the inner or opposed faces of the wings having cam-like elements for guiding the opposed series of fastener elements as they approach or recede. The continued successful operation 15 of such a slider is dependent upon the accurate maintenance of the relative positions of the wings, but as the wings can be united at or near one end only, and as the slider is subjected to severe strains tending to wedge 20 the wings apart and otherwise to distort it, difficulty has been experienced in making the slider sufficiently rigid without making it unduly heavy and cumbersome.

From practical consideration it is desirable 25 to keep the slider as small and light in weight as possible and in particular to avoid making it unduly thick from front to rear, while low cost of production also is an essential desideratum. Commonly such sliders have been made from sheet metal parts, the 30 necessary stiffness and strength being obtained by assembling a yoke member with the wings, but this mode of manufacture requires the formation of several independent 35 pieces and their subsequent assemblage, all of which increases the cost of production, and even when completed such built-up sliders are not always of pleasing appearance or as light in weight or as strong as might 40 be desired.

Certain attempts have been made to form 45 sliders by a die casting process or similar procedure, in accordance with which the wings and the reinforcing element are made of unitary or integral construction, such a process apparently being disclosed in the British patent to Kuhn-Moos No. 14,358, dated January 19, 1912. While this latter 50 mode of procedure results in a stiff and strong slider, the process is difficult and expensive, the slider is heavier than is to be desired, and an excess amount of metal is consumed.

In accordance with the present invention I combine the advantages of the sheet metal 55 construction, to wit, light weight, low production cost, and small dimensions, with the inherent stiffness and rigidity of a unitary construction such as heretofore has not been obtainable so far as I am aware only by die 60 casting or a similar process, while the improved slider is capable of withstanding heavy stress without substantial distortion.

In the accompanying drawings;

Fig. 1 is a fragmentary front elevation to 65 large scale, showing a fastener of the general type above referred to provided with a slider constructed in accordance with the present invention;

Fig. 2 is a front elevation of the same slider 70 removed from the stringers;

Fig. 3 is a side elevation of the slider of Fig. 2;

Fig. 4 is a plan view of a blank suitable 75 for use in making the improved slider and indicating certain preliminary operations which have been performed upon the blank;

Fig. 5 is an edge view of the blank of Fig. 4;

Fig. 6 is a section substantially on the line 80 6—6 of Fig. 4;

Fig. 7 is a view similar to Fig. 4 but showing the blank at a subsequent stage of the process;

Fig. 8 is an edge view of the blank as 85 shown in Fig. 7;

Fig. 9 is a section on the line 9—9 of Fig. 7;

Fig. 10 is a section substantially on the line 10—10 of Fig. 3; and

Fig. 11 is a fragmentary section on the line 11—11 of Fig. 10.

In Fig. 1 of the drawings the numerals 1 and 2 designate a pair of stringers or tapes of the usual kind to whose opposed edges 95 the series of fastener elements 3 are secured. As here shown, the fastener elements of the two series are of identical construction, each comprising a socket and a locking pin, the fastener elements of the opposed series being 100 staggered so that they may be brought into intermeshing engagement wherein the locking pin of the element of one series engages the socket of the next adjacent element of the opposed series. While this type of fastener is herein illustrated, it is to be under-

stood that the improved slider 4 forming the immediate subject matter of the present invention is applicable to other types of fastener as well as that here specifically illustrated.

Referring to Fig. 4, I have shown a blank, preferably blanked from sheet metal, which is manipulated as hereinafter described to form the slider proper. This blank comprises the relatively wide end portions or wings 5 and 6 designed to constitute the front and rear plates of the slider, said wide end portions being integrally united by the relatively narrow band or neck 7.

15 As above stated, this blank is preferably formed by blanking it from a piece of sheet material, and either concomitantly with the blanking operation or subsequently thereto I form the longitudinally extending shallow ridge 8, Fig. 6. This ridge runs the entire length of the neck and to the free ends of the wings 5 and 6. At the same time with or subsequent to the formation of the ridge 8 I pierce the material of one 20 of the wings, for example, the wing 6, to form openings 11 adjacent to the opposite edges of the ridge 8 and preferably near the end of the latter.

Having provided the blank with this ridge 25 and openings, I next proceed to fold the blank preferably by compressing the ridge 8 laterally so that the opposite portions of the ridge 8 are brought into substantial parallelism as in Fig. 9, forming the walls 30 8^a and 8^b of a narrow rib 12 projecting perpendicular to the plane of the blank and of the same longitudinal dimensions as the original ridge 8. In thus folding the ridge 8 I cause the openings 11 and 12 to be brought 35 into alignment, thus forming in effect a single opening 13 extending through the entire thickness of the rib 12 closely adjacent to the wing 6. Since the rib 12 is formed by a folding operation the strength of the 40 metal is not impaired, whereas, were the rib embossed, the metal would be drawn out, thinned and strained, and the resulting slider would have but a small percentage of the strength of the slider made by folding.

45 50 Either prior to or subsequently to the folding of the ridge to form the rib 12 I prefer to indent the neck 7 at opposite sides of the ridge or rib to provide elongate depressions 14 and 15 respectively, forming 55 corresponding bulges or rounded surfaces upon the opposite side of the blank, such rounded surfaces being indicated at 14^a and 15^a in Fig. 11.

To provide a suitable finish for the ends 60 of the rib 12, I prefer to cut out a small triangular section 9 at each end of the ridge 8, which results, as shown in Fig. 8, in giving the ends of the folded rib 12 an inclined or beveled form.

Either prior to or subsequently to the

completion of the rib 12 and the formation of the indentations 14 and 15, I turn in the lateral edges of the wings 5 and 6 to form the guide flanges 16 and 17 respectively, such flanges being intended to constitute the 70 outer walls of guide channels for the fastener elements 3, while the rounded projections 14^a and 15^a on the inner surface of the neck constitute the inner walls of these channels.

Having completed the above operations, I now bend the blank at the neck portion transversely of its length so as to curve the neck and bring the wings 5 and 6 into substantial parallelism as indicated in Fig. 3. 75 The slider is now substantially complete except for the provision of a pull device to facilitate operation of the slider. Such a pull device 18 may be blanked from sheet material and is provided with an opening 80 at 19 and with opposed pintle lugs 20 and 21. In applying the pull device 18 to the slider the pintle lugs 20 and 21 may be bent or sprung apart sufficiently to enable them to be snapped into the opening 13 from opposite sides, the opening 19 in the pull device receiving the end portion of the rib 12. Preferably the opening 13 is more or less elongate to permit some up and down movement of the pull device whereby to facilitate actuation of the slider in opposite directions, but such elongate opening is not necessary and a simple pivotal connection between the pull device and the slider proper is all that is essential.

100 The slider thus provided is applied to the stringers in the usual manner, the fastener elements being disposed in the divergent channels provided by the flanges 16 and 17 and the rounded projections or bulges 14^a and 15^a at the inside of the neck. The slider is now actuated in the usual manner to bring the fastener elements 3 into engagement or to disengage them as the case may be. It will be noted that the slider proper 105 is of unitary construction consisting of a single piece of metal and that it is produced by blanking and folding operations of a type which may be performed with extreme rapidity and by slightly skilled labor. 110 There are no parts to become separated after the slider is completed, with the possible exception of the pull device, while the slider proper is of extremely rigid and substantial construction, the integral fold of metal constituting the rib 12 furnishing the maximum stiffness for a given amount of material.

115 While a single longitudinal rib substantially midway of the width of the slider is 120 here described and shown, I contemplate that under some circumstances more than one rib may be provided if such should prove desirable. I also contemplate that 125 variations in dimensions of the parts and 130

in the sequence of steps employed in the production of the slider may be made as circumstances may indicate to be desirable and further that the pull device may be attached in other ways than that here shown or that more than one pull device may be provided if desired.

I claim:

1. A slider for separable fasteners of the class described comprising spaced wings of sheet material united at one end by a neck, and a fold in the material of said neck constituting a projecting stiffening rib.

2. A slider comprising flat wings of sheet material connected adjacent to one end and having inwardly directed edges forming diverging channels, said slider having a stiffening yoke consisting of a fold in the sheet material, said fold being integrally united with the connection between said wings and having ends extending longitudinally of each wing toward the free ends of the latter.

3. A slider comprising wings defining diverging channels, and a relatively narrow neck connecting the wings at a point between the diverging channels, said neck and wings consisting of a unitary piece of sheet material, the slider having an external U-shaped stiffener yoke consisting of an integral fold 30 in the sheet material.

4. A slider for separable fasteners of the class described comprising a piece of sheet material doubled to provide spaced front and rear wings and a neck connecting said wings at one end, and an external fold in the sheet material constituting a continuous rib projecting from the outer surface of the wings and said neck.

5. A slider for separable fasteners of the class described comprising an integral piece of sheet material doubled to provide spaced front and rear wings and a neck connecting said wings at one end, and a U-shaped stiffener yoke consisting of a fold in the sheet material, the central portion of the yoke projecting from the neck and the legs of the yoke projecting from the respective wings.

6. A slider for separable fasteners of the class described comprising a piece of sheet material provided with wide end portions or wings and a relatively narrow neck portion uniting the wings, the neck being curved and the wings being spaced apart and substantially parallel, said piece of material having a longitudinally extending fold providing a stiffening rib, said rib extending around the neck and longitudinally of the wings.

7. A slider for separable fasteners of the class described comprising a piece of sheet material provided with wide end portions or wings and a relatively narrow neck portion uniting the wings, the neck being curved and the wings being spaced apart and substantially parallel, said piece of material

having a longitudinally extending fold providing a stiffening rib, said rib extending around the curved neck and longitudinally of the wings, the end portions of the rib being of diminishing height

70

8. A slider for separable fasteners of the class described comprising spaced wings of sheet material, and a fold in the material of at least one of said wings, said fold projecting outwardly from the exterior surface of the wing to form a stiffening rib, and a pull device attached to said rib.

75

9. A slider for separable fasteners of the class described comprising spaced wings of sheet material, and a fold in the material of at least one of said wings, said fold projecting outwardly from the exterior surface of the wing to form a stiffening rib, said rib having a transverse opening therethrough, and a pull device having a pivot member engaging said opening.

80

10. A slider for separable fasteners of the class described comprising spaced wings of sheet material, and a fold in the material of at least one of said wings, said fold projecting outwardly from the exterior surface of the wing to form a stiffening rib, said rib having an elongate transverse opening therethrough, and a pull device having oppositely directed pintle members engaging said opening.

85

11. A slider for separable fasteners of the class described comprising a piece of sheet material doubled to provide spaced wings and a neck uniting the wings, the material of the neck having an outwardly directed stiffening fold at its center, and being bowed inwardly at each side of the fold to provide rounded guide surfaces at its inner side.

90

12. A slider for separable fasteners of the class described comprising a piece of sheet material doubled to provide spaced wings and a neck uniting the wings, said piece of material having a longitudinally extending outwardly projecting fold at its center, said fold extending over the neck and longitudinally of the wings, the neck at each side of the fold having a shallow inwardly directed rib providing spaced guide surfaces at its inner side.

105

13. That process of making a slider of the class described comprising as steps providing a sheet metal blank with an integral elongate fold having its opposite side walls in contact, and bending the blank transversely to the length of the fold to bring its end portions into parallel relation with the fold projecting from the outer surface of the blank.

110

14. That process of making a slider of the class described which comprises as steps blanking a blank from sheet material, said blank having wide end portions or wings connected by a relatively narrow neck, folding the blank to form a rib lengthwise of

115

120

125

130

the neck and wings, and bending the neck to bring the wings into substantial parallelism, the bending being so performed as to cause the rib to project from the outer surface of the wings.

15. That process of making a slider of the class described which comprises preparing a sheet metal blank having wide end portions or wings and a relatively narrow neck connecting said wings, forming a ridge extending longitudinally of the neck and wings, laterally folding said ridge to form a rib, and bending the neck to bring the wings into substantial parallelism.

16. That process of making a slider of the class described which comprises preparing a sheet metal blank having wide end portions or wings and a relatively narrow neck connecting said wings, forming a ridge extending longitudinally of the neck, folding said ridge to form a narrow outstanding rib, and bending the neck and its rib until the wings are substantially parallel.

17. That process of making a slider of the class described which comprises as steps preparing a blank from sheet material, said blank having a relatively narrow neck uniting wider end portions or wings, forming a longitudinally extending shallow U-shaped ridge in the blank, piercing the blank at opposite sides of the ridge to form openings, and laterally compressing the ridge to bring its sides into contact whereby to form a rib-like fold substantially perpendicular to the plane of the strip and to bring said openings into alignment.

18. That process of making a slider of the class described which comprises preparing a sheet metal blank having wide end por-

tions or wings and a relatively narrow neck connecting said wings, piercing one wing to provide laterally spaced openings, forming a fold in the material of the blank, said fold extending longitudinally of the neck and into the wings, the folding of the material bringing said openings into alignment, and connecting a pull device to the slider by means engaging said aligned openings.

19. That process of making a slider of the class described which comprises preparing a sheet metal blank having wide end portions or wings and a relatively narrow neck connecting said wings, folding the metal of the neck to provide a narrow rib projecting substantially perpendicular to the plane of the neck and extending longitudinally thereof, impressing the metal on either side of the rib to form low ridges upon the opposite face of the neck, and bending the neck to bring the wings into parallel relation with the rib at the outer side of the bend.

20. That process of making a slider of the class described which comprises preparing a sheet metal blank having wide end portions or wings and a relatively narrow neck connecting said wings, forming a longitudinal fold in the blank extending along the neck and into each wing, turning in the lateral margins of the wings to define the outer edges of the guide channels, indenting the neck at opposite sides of the fold to form the inner walls of said channels, and bending the blank at the neck to bring the wings into substantially parallel relation.

Signed by me at Berlin, Connecticut, this 27th day of December, 1926.

GEORGE E. PRENTICE.
